UNITED STATES PATENT OFFICE.

ROBERT GILCHRIEST, OF LOUISVILLE, KENTUCKY.

REGULATOR FOR GAS-BURNERS.

SPECIFICATION forming part of Letters Patent No. 611,471, dated September 27, 1898.

Application filed November 19, 1897. Serial No. 659,133. (No model.)

To all whom it may concern:

Be it known that I, ROBERT GILCHRIEST, a citizen of the United States, and a resident of Louisville, in the county of Jefferson and 5 State of Kentucky, have invented certain new and useful Improvements in Regulators for Gas-Burners; and I do declare the following to be a full, clear, and exact description of the invention, such as will enable others skilled 10 in the art to which it appertains to make and use the same, reference being had to the accompanying drawings, and to letters of reference marked thereon, which form a part of this specification.

15 Figures 1 and 2 of the drawings are sectional views of a gas-burner tip, showing the use of the invention. Fig. 3 is a cross-section on line x x , Fig. 1. Figs. 4 and 5 are detail views showing different forms of the 20 plug. Fig. 6 is a vertical section of the plug shown in Fig. 5. Fig. 7 is an end view of the same, and Fig. 8 is a perspective view of a device for making the plugs.

This invention has relation to a regulator 25 for gas-burners whereby the consumption of gas may be controlled to suit the requirements; and it consists in an obstructive device of peculiar character placed within the tip of the burner for the purpose of retarding the flow of gas from the service-pipe to 30 the point of combustion, with means whereby said device may be adjusted to cause a greater or less retardation of the flow.

The invention also consists in the combination, 35 with an ordinary burner-tip, of a plug or obstruction of this character, together with means for adjustably securing the plug in the tip.

Referring to the accompanying drawings, 40 the letter A designates the tip of an ordinary gas-burner. B designates one of the plugs or obstructions, which is designed to be adjustably secured in such tip for the purpose of retarding the flow of gas, as above stated. 45 This plug or obstruction may be constructed of stone, metal, composition, wood, or any suitable material. In the form shown in Fig. 4 it has two flattened sides b b , which provide passages or ways to permit a partial flow 50 of gas thereby. It may, however, have but one flattened side or as many as may be desired, or one or more of the sides may be

grooved, as indicated at c in Fig. 5. The plug is also tapered upon its flattened or grooved sides, as indicated at d , being largest 55 at its lower end. Extending diametrically through the plug, one above the other, are two or more small pin-holes f , and formed through the lateral walls of the tip at opposite points are similar pin-holes g , said holes 60 f and g being to receive a pin h , by means of which the plug is held in place. When the plug is secured by passing the pin through the lower hole f , it will be readily seen that a greater retardation of gas takes place than 65 when it is inserted through the upper of said holes.

The only change required in the pillar and tip of an ordinary gas-burner in order to permit this invention to be applied thereto is the 70 provision of the pin-holes g in the tip.

The device not only restricts and regulates the consumption of gas according to the requirements, but it also prevents to a large extent the feature known as "blowing." 75

When the plugs are made of metal or other material which can be shaped by casting, they can be conveniently made by means of a small two-part mold K , such as shown in Fig. 8. This mold has two mold-cavities k , 80 with transverse grooves k , in which wires K are placed, said wires being subsequently withdrawn to provide in the plug the pin-holes f .

One or both of the pin-holes g in the tip 85 should be countersunk to seat the head of the pin h flush with the surface, so that said head will not present an obstruction to the insertion of the tip in the pillar.

Having thus described my invention, what 90 I claim as new, and desire to secure by Letters Patent, is—

1. The herein-described device for regulating the flow of gas in gas-burners, said device comprising a small solid plug adapted to fit 95 within an ordinary gas-burner tip, said plug being of increasing diameter toward its base, and partially cut away upon one or more of its sides to form gas-passages, together with means whereby the said plug may be adjusted 100 longitudinally in the tip and secured in its different adjustments for the purpose of changing the area of the said passages, substantially as specified.

2. The combination with a gas-burner tip, having opposite pin-holes in its lateral walls, of a regulating or retarding device comprising a small tapered plug inserted into the lower end of said tip and formed with two or more pin-holes extending diametrically therethrough either one of which may be brought to register with the holes of the tip, said plug also having one or more of its sides

shaped to provide a gas-passage thereby, substantially as and for the purpose set forth.

In testimony whereof I affix my signature in presence of two witnesses.

ROBERT GILCHRIEST.
